UNITED STATES PATENT OFFICE.

THEODORE W. WIDENMANN AND MARCUS R. HARRIS, OF DETROIT, MICHIGAN, AS-SIGNORS TO PRINTING REGISTER CO., OF DETROIT, MICHIGAN, A CORPORATION OF MICHIGAN.

PAPER-ROLL MOUNTING FOR AUTOGRAPHIC REGISTERS.

Application filed January 2, 1925, Serial No. 295. Renewed June 29, 1928.

This invention relates to a paper roll mounting particularly for autographic registers and the object of the invention is to provide a means for holding a series of paper rolls in alignment so that the sheets may be fed from an autographic register in superimposed relation with the edges thereof in alignment.

Another object of the invention is to provide a mounting for the paper rolls in which a tension is maintained on each roll so that the roll will not revolve except as paper is withdrawn therefrom.

Another object of the invention is to provide an autographic register in which the rolls may be easily removed from the register or easily replaced therein and when positioned in the register the rolls are automatically brought to alignment by the automatic tension device.

A further object of the invention is to provide an autographic register which may be very easily loaded and unloaded, which maintains the paper strips in the rolls in alignment and which maintains a tension on the rolls yieldably resisting withdrawal of the paper strips from the rolls.

These objects and the several novel features of the invention are hereinafter more fully described and claimed and the preferred form of construction by which these objects are attained is shown in the accompanying drawings in which—

Fig. 1 is a horizontal section through an autographic register embodying my invention.

Fig. 2 is an enlarged view of a portion of the register taken from the side of Fig. 1.

Fig. 3 is a section taken on line 3—3 of Fig. 2.

Fig. 4 is a perspective view of the roll tension device.

Fig. 5 is a section taken on line 5—5 of Fig. 4.

As shown in Fig. 1 the autographic register is provided with a base 1 on which the register casing 2 is mounted. The casing 2 is provided with a removable side 3 through which the machine may be loaded or unloaded. The member 4 is secured to one side of the casing 2 by the screws or rivets 5 and this member 4 is formed of heavy sheet metal with the struck out portions or bosses 6. These bosses are all of exactly the same length with

the end faces thereof in the same plane and 55 a stud shaft 7 is secured to each boss and extends cross wise of the casing 2 at a right angle to the face of the respective boss. The paper rolls 8 are slipped over the stud shafts 7 as shown in Figs. 1, 2 and 3 and are rotatable thereon and each stud shaft at the end protruding from the paper roll is provided with a pair of vertical slots 9 and 10. A member 11 shown more particularly in Fig. 4 is provided having a central vertical notch 12 60 providing edges 13 and 14 adapted to engage in the slots 9 and 10 and the member 11 is provided with struck up lugs 15 and 16 by which the device may be grasped in the fingers. The member 11 is also provided with 65 an angularly extending portion 17 to which a flat spring 18 is secured by the bolt 19 and the angular portion 17 causes the spring 18 to extend outwardly from the member 11 to engage the end of the respective paper roll as 70 shown in Figs. 1 and 3.

In operation the side 3 of the autographic register is removed and the rolls 8 are slipped onto the stud shafts 7 until the paper rolls engage the bosses 6 as shown in Fig. 80 1. At this time the members 11 are grasped by the portions 15 and 16 and by inserting the edges 13 and 14 in the slots 9 and 10 the member 11 may be moved downwardly over the ends of the stud shafts until the 85 upper ends of the notches 12 engage the stud shafts. The springs 18 as shown in Fig. 3 engage the ends of the paper rolls 8 in this position and hold the respective rolls in engagement with the respective bosses 6 and, 90 as the end faces of the bosses are in the same plane the paper rolls are thus mounted in alignment. The rolls are unwound by drawing the sheets therefrom to the right of Fig. 95 1 and therefore the superimposed sheets of the different rolls are in alignment at the opposite edges. The springs 18 while holding the rolls in proper position also act as roll tension devices and yieldably resist rotation of the rolls so that a tension is placed 100 on the different strips at all times and a sudden pull on the strips will not cause the rolls to over-run. The parts of this device with the exception of the stud shafts may all be made of sheet metal thus providing a cheap construction which at the same time provides a 105 perfect roll mounting.

From the foregoing description it becomes

evident that the device is very simple and efficient in operation, will not easily get out of order, is composed of few parts and is of consequent low manufacturing cost and provides 5 a device which accomplishes the objects described.

Having thus fully described our invention, its utility and mode of operation, what we 10 claim and desire to secure by Letters Patent of the United States is—

1. A mounting for paper rolls comprising a stationary supporting member having a series of bosses extending therefrom, the faces of the bosses all being in the same plane, a 15 stud shaft secured in each boss and extending at a right angle to the face thereof, a paper roll rotatably mounted on each stud shaft, the end of each stud shaft opposite the boss being provided with a pair of slots on opposite sides 20 thereof, a sheet metal member engaging in the slots of each stud shaft, the upper edge of each sheet metal member being bent outwardly at an angle, and a flat spring secured to the bent portion of each sheet metal member and 25 extending outwardly into engagement with the end of the respective paper roll.

2. A mounting for paper rolls comprising a stationary supporting member having a series of bosses extending therefrom, a stud shaft 30 extending from each boss, the bosses being each provided with a flat face about the re-

spective stud shaft and all flat faces being in the same plane, a paper roll rotatably mounted on each stud shaft and engaging the flat face of the respective boss, each stud shaft 35 being provided with a pair of slots in the end opposite the boss, a member engaging in the said slots of each stud shaft, and a spring carried by each member yieldably resisting rotation of the paper roll and holding the 40 paper roll in engagement with the flat face of the boss.

3. A mounting for paper rolls comprising a stationary supporting member having a series of bosses extending therefrom, a stationary 45 stud shaft secured in each boss, the bosses all having an end surface in the same plane, a paper roll rotatably mounted on each stud shaft, the unsupported end of the shafts being notched, and an aligning and tensioning 50 device consisting of a bifurcated member providing a central notch, the opposite sides of which engage in the notch provided therefor in the shaft end to support the same in place, a spring member carried by the bifurcated 55 member and yieldingly engaging the respective roll end.

In testimony whereof we sign this specification.

THEODORE W. WIDENMANN.
MARCUS R. HARRIS.
